WASHING MACHINE

Dave Hirstel, San Francisco, Calif., assignor of
one-half to Ferdinand Bendheim, Palo Alto,
Calif.

Application June 22, 1934, Serial No. 731,839

9 Claims. (Cl. 74—75)

This invention relates to tray washing machines of the class adapted to be attached to the standard laundry wash trays or tubs, however the same mechanism may be used on other types of washing machines.

Among the objects of the invention one is to provide a mechanism adapted to be driven by a motor, that is simple, and which has few wearing parts.

10 Another object is to provide means to transmit the power of the motor to a master shaft from which the washing agitator and wringer may be operated separately or together as desired.

Another object is to provide a reversible motor 15 to drive the master shaft whereby the master shaft may transmit an oscillating motion to the clothes agitator, and a continuous rotary motion to the wringer, the reversing of the motor reversing the wringer without affecting the action of 20 the agitator.

Another object is to provide means to swing the wringer out of the way when not needed, and means to lock it in the operating position, and out of the operating position, and means to lock 25 the rollers of the wringer from turning when the wringer is swung out of the operating position.

A further object of the invention is to provide 30 means to throw the agitator out of gear, and separate means to throw the wringer out of gear when the motor is running or not.

Another object is to provide an inclosed housing 35 for the moving parts of the machine, and the provision of means to use a rotary seal on the agitator shaft so that the splash system of lubrication may be used, the housing to be made preferably of sheet steel, the base member to be of steel or a certain type of plywood.

Another object is the means for clamping the 40 washing machine to the laundry tray in a resilient grip to allow for the expansion and contraction of the base of the machine when steel is used therefor to reduce the vibration when the machine is operating.

45 Another object is the use of an automatic cut out switch for the motor whereby the motor will stop instantaneously if anything is caught in the wringer or when the machine is overloaded, the same switch being used to reverse the motor.

50 Another object is to provide the use of a drive chain which will act as a shock absorbing means.

Other objects will appear to those skilled in the art to which it appertains as the description progresses.

55 An embodiment of the invention is shown in the accompanying drawings in which the same reference numeral is applied to the same portion throughout the several views, and of which there may be modifications.

60 Figure 1 is a front view of the machine as ap-

plied to the laundry tray, the tray and parts of the machine being in section.

Figure 2 is a plan of the washer partly in section, and showing the wringer out of operative position in dotted lines.

5 Figure 3 is a section on line 3—3 of Figure 2.

Figure 4 is a section on line 4—4 of Figure 3.

Figure 5 is a view partly in section showing the arrangement of clutches and means for locking the wringer out of operative position.

10 Figure 6 is a plan view taken on line 6—6 of Figure 5, but not showing the gears.

Figure 7 is a sectional view of the safety locking means.

15 Figure 8 is a sectional plan of the clutch for operating the agitator member.

Figure 9 is a sectional view of means for clamping the machine to the laundry tray.

20 Figure 10 is a plan of the means of clamping the tray.

25 Figure 11 is a modified form of the tray clamping means.

Figure 12 is a modified form in plan for operating the agitator.

30 Figure 13 is a side view of the device shown in Figure 12.

The construction in detail of the washing machine comprises a base member 1 which is adapted to set on the back left hand top portion of the laundry tray 2 which may be any kind of a receptacle, but in this instance a standard laundry tray having the partition 3 dividing it into two compartments is shown.

35 Mounted on the base 1 is the motor 4 having its shaft 5 connected to a drive shaft 6 by means of a coupling 7, suitable bearings 8 and 9 being provided in the housing 10 which is attached to the base 1. Fixed to the shaft 6 is the worm 11 in mesh with the worm wheel 12 fixed on the shaft 13 so that this vertical master shaft is 40 driven continuously when the motor is running.

The vertical shaft 13 has the lower bearing 14 in the housing 10, and the upper bearing in the top of the rotatable housing 15 as shown at 45 16, the rotatable housing being mounted to turn on the stationary vertical housing 17 which is fastened to the housing 10 by means of the flange 18 and the bolts 19.

The rotatable housing is adapted to carry the wringer 20 on the projection 21 of the housing 50 secured by the ears 22 and 23 on the wringer by means of the bolts 24.

The lower roll 25 of the wringer has the shaft 26 fixed to a bevel gear 27 which is in mesh with the pinion 28 freely mounted on shaft 13, and 55 supported by the collar 29.

The pinion 28 has co-acting jaws for the slideable jaw clutch 30 which slides on the key 31 on the shaft 13, the clutch being raised or lowered by the handle 32, short shaft 33, crank 34 and 60

pivoted block 35 in the groove 36 of the clutch member, when the clutch is down the jaws are in mesh and the wringer rolls are driven by the shaft.

5 In the present invention there is only one position of the wringer in which the clutch may be thrown into mesh, and that is in the operative position shown in Figure 2 in full lines.

In any other position the clutch is locked 10 against downward movement, and this locking means consists simply of block 37 which engages the groove of the clutch and extends down to the top of the stationary portion of the housing 38 and slides around on the top edge thereof, a 15 notch 39 in the edge allows the block to come down to bring the clutch into mesh so the motor can drive the wringer through the vertical shaft, when the clutch is raised the wringer is out of gear and may be swung around to the position 20 shown in the dotted lines in Figure 2 and to hold it in that position a shallow notch 40 is provided which allows the block to enter but holds the clutch out of mesh as shown in Figure 5.

The housings 15 and 17 are provided with 25 flanges 41 and 42 and are held in position by the two half collars 43 and 44 which are secured by the bolts 45.

Mounted in the housing 18 is the agitator shaft 46 to which is adjustably fixed the agitator 47 located in about the center of the tray compartment, the shaft has the bearings 48 and 49 in the housing, and the bearing 49 is provided with a nonleakable oil seal 49' of the rotary type which prevents the possibility of oil leaking into the 35 wash tray.

The agitator is given an oscillating movement by means of the eccentric 50 rotatably mounted on shaft 13 and having jaws 51 adapted to mesh with the jaws of the clutch member 52 slidably 40 mounted on the shaft and key 53, the clutch being operated by the handle 54, a short shaft 55, crank 56, and pivoted block 57 in the groove of the clutch member to slide it up or down.

The eccentric is adapted to rotate in a slideable 45 block 58 in the frame 59 which is secured to a sprocket wheel 60 by the rivets 61 or other suitable means, the sprocket being mounted on the pin 62 in the housing 18 spaced from the shaft 13, a slot 63 allows for the oscillating movement of 50 the sprocket, and the oscillating movement of the sprocket is transmitted by a chain 64 to the agitator by the sprocket 65 fixed on the shaft 46.

The base 1 of the machine is clamped to the tray by the resilient means shown in Figures 9, 55 10, and 11 to allow for the expansion and contraction of the metal in the base caused by the changing from hot to cold water in the washing operation. In Figures 9 and 10 the guide 66 is attached to the base in any suitable way such as 60 welding, and a threaded bolt 67 is mounted therein, a spring member 68 is fixed to the end of the bolt and is adapted to press on the side of the tray acting against a clamp member 69 which is 65 pressed by the spring 70 and adjusted by the nut 71, and the bolt is held in the adjusted position by the nuts 72 and 73.

A strip of resilient material 74 may be used to take the vibrations of the machine when running.

70 In the modified form of clamp shown in Figure 1 the resilient means consists of rubber or other resilient material 75 in the top and sides, and a clamp 76 fixed to the bolt 68, and a clamp 77 adjusted by the nut 78 which provides a resilient 75 means of clamping the machine to the tray.

Another modified form of the invention is the use of hard wood of the highest grade plywood construction bound together with phenol formaldehyde resin to make it fire resistant, water-proof, and germ proof.

5 The modified form for producing the oscillating motion of the agitator shown in Figures 12 and 13 the eccentric 50 on the shaft 13 operates an oscillating arm 79 by means of the sliding block 58 in the opening 80 in the arm, the arm 10 being pivoted on the shaft 66.

The oscillating movement of the arm is transmitted to the agitator by means of a metal ribbon 81 which is secured to the arm at 82 and passes over the pulleys 83 and 84 to the pulley 85 15 to which it is secured at 86.

The motor is provided with a reversing switch 87 which controls the operation of the machine, the direction of rotation of the master shaft 13, and the automatic cut out device is located in 20 the switch casing.

In operation the clothes and water being placed in the tray in the usual way, the wringer is thrown out of gear and swung around out of the way of the washing operation, the motor oscillates the 25 agitator until the clothes are clean, the clutch of the agitator is then thrown out by the handle 54 and the handle 32 on the wringer is raised enough to release it from the shallow notch 40, whereupon the wringer is swung around into operating 30 position and the handle 32 then throws the clutch in operation, and the block into the notch 39 thereby starting the operation of the wringer, the motor switch being set so the wringer will convey the clothes into the other compartment of the 35 tray. The motor is reversed to convey the clothes back into the first compartment into blueing water, and then again the wringer is reversed to convey the clothes back to complete the operation.

40 The machine is left clamped to the tray preferably but may be moved if desired.

From the foregoing description it will be seen that a very simple and effective machine for the purpose has been evolved.

45 Particularly by the employment of the mechanism disclosed in the modified form shown in Figs. 12 and 13 of applicant's drawings are efficacious results obtained. By thus providing between the mechanism for effecting oscillatory movement, which includes the eccentric 50, and the element to be oscillated, which includes the shaft 46 and the agitator 47 for providing the washing action, a drive connection comprising a metal band or ribbon 81, a silent, vibrationless 50 operation is assured because of the elimination of gear or sprocket arrangements inevitably resulting in noise and vibration.

55 In this modification of the invention it will also be noted that the band 81, by being fixedly secured to the oscillating member 79, such as indicated at point 82, provides a belt drive connection which will not slip. Because of the provision of this means the whipping or oscillation of the element to be oscillated, namely, the agitator 47, will be immediately responsive or synchronous with each change of direction of oscillatory movement of member 79. Thus, the agitator 47 will not be subject to any period of dwell or lost motion at any time during the operation of the oscillating 70 mechanism, but instead will whip back and forth continuously and smoothly. In other words, in this form of my invention the back-lash which is ordinarily encountered in drive connections embodying gear or sprocket arrangements and which 75

impairs the efficiency of the mechanism as well as its proper washing action is avoided. Not only, therefore, by employing a metal band or ribbon as a drive connection between the oscillating mechanism and the element to be oscillated is there provided desirable quietness and smoothness of operation because of the elimination of noisy or vibrating gears, but more effective washing action and increased life of the mechanism is obtained because of the complete elimination of lost motion and back-lash.

This modification, like the form disclosed in the remaining figures, is also adapted to be employed in a complete washing machine unit as well as in the so-called tray type of washing machine illustrated in the drawings of the present application.

Having thus described my invention what I desire to secure by letters patent of the United States is as follows, but modifications may be had in carrying out the invention as shown in the accompanying drawings and in the particularly described form thereof within the purview of the annexed claims.

25 I claim:

1. A washing machine of the class described comprising a base, a housing on said base, a horizontal drive shaft journaled in said housing, a motor to drive said shaft, a vertical shaft driven by said horizontal shaft, a vertical agitator shaft journaled in said housing and extending through the bottom of said housing, a sprocket wheel, a short shaft for said sprocket fixed in said housing and spaced from the vertical shaft, an opening in said sprocket to allow said sprocket to oscillate on the vertical shaft, an eccentric on the vertical shaft, a bearing block for said eccentric, a frame fixed to said sprocket, a guideway in said frame for said block, a sprocket wheel on said agitator shaft and a chain around said sprocket wheels.

2. A washing machine of the class described comprising a base adapted to be clamped to a laundry tray, a housing on said base, a horizontal shaft journaled in said housing, a worm on said shaft, a vertical shaft journaled in said housing, a worm wheel on said shaft in mesh with said worm, an eccentric freely mounted on said vertical shaft, a sprocket wheel forming a bearing for said eccentric, clutch teeth on said eccentric, a slideable clutch member having teeth to engage said clutch teeth, a frame having a guideway for said slideable block, a sprocket wheel having a pivot pin in the housing and spaced a short distance from said vertical shaft, means to fix said frame to said sprocket wheel, an oscillating shaft journaled in said housing, a sprocket wheel on said shaft, and a chain for said sprocket wheels.

3. A washing machine of the class described comprising a base, a housing on said base, a horizontal drive shaft journaled in said housing, a motor to drive said drive shaft, a vertical shaft driven by said drive shaft, a second vertical shaft journaled in said housing and extending through the bottom of said housing, a pulley wheel, a short shaft for said pulley wheel fixed in said housing and spaced from the first vertical shaft, an opening in the pulley wheel to allow said pulley to oscillate on the first vertical shaft, an eccentric on the first vertical shaft, a bearing block for said eccentric, a frame fixed to said pulley, a guideway for said block in said frame, a frame fixed to said pulley wheel, a pulley wheel on said second vertical shaft and a belt around said pulley wheels.

4. A washing machine of the class described comprising a vertical shaft adapted to be driven, an eccentric connected to said vertical shaft, a slideable block for said eccentric, an oscillating shaft, an oscillating arm having a guideway for said slideable block and pivoted on said oscillating shaft, a pulley fixed on said oscillating shaft, guide pulleys spaced apart, and an endless flexible belt fixed to said arm and passing around said guide pulleys and fixed to said pulley on the oscillating shaft.

5. In a washing machine having an agitator to be oscillated, driving mechanism to effect oscillatory movement including a drive shaft, an eccentric connected to said drive shaft, a slideable member engaged by said eccentric, and a pivoted oscillating arm having a guideway for said slideable member; and a belt driving connection between said mechanism and said agitator comprising a metal ribbon, said ribbon being fixedly secured to said mechanism to effect oscillatory movement of said agitator immediately responsive to change of movement of said mechanism and without backlash.

6. Driving mechanism for a washing machine 25 agitator or the like, comprising a pulley connectable with said agitator, mechanism to effect oscillatory movement and including a pulley and an oscillating arm, a ribbon passing over said pulleys, and means securing said ribbon to said pulley 30 connectable with said agitator shaft and said oscillating arm whereby change of directional movement of said mechanism is immediately transmitted to said ribbon.

7. A washing machine of the class described, 35 comprising a drive shaft, an eccentric connected to said drive shaft, a slideable member engaged by said eccentric, an agitator shaft adapted to be oscillated, an arm pivoted about said agitator shaft and having a guideway for said slideable 40 member, pulley means connected with said agitator shaft, other pulley means adjacent said drive shaft, and an endless flexible belt, fixed to said arm and to said pulley means connected with said agitator shaft and passing around said other 45 pulley means.

8. A washing machine of the class described, comprising a drive shaft, an eccentric connected to said drive shaft, a slideable member engaged by said eccentric, an agitator shaft adapted to be 50 oscillated, an oscillating arm pivoted about said agitator shaft and having a guideway for said slideable member, spaced apart pulley means adjacent said drive shaft, other pulley means about 55 said agitator shaft, and an endless flexible metal belt passing around said pulley means for imparting oscillating movement from said arm to said agitator shaft, said belt being fixed to said other pulley means and to said oscillating arm.

9. Driving mechanism for a washing machine agitator comprising a pulley connectable with said agitator; mechanism to effect oscillatory movement of said agitator including a drive shaft, an eccentric connected to said drive shaft and an oscillating member connected with said eccentric; and a metal ribbon driving connection between said mechanism and said agitator, said ribbon being fixedly secured to said oscillating member and to said pulley to effect oscillatory movement of said agitator immediately responsive to change of movement of said mechanism and without backlash.
